UNITED STATES PATENT OFFICE.

WALTER A. DANN, OF CINCINNATI, OHIO.

DESIGN FOR A RADIATOR CAP.

Application filed October 26, 1921. Serial No. 510,680. Term of patent 8½ years.

To all whom it may concern:

Be it known that I, WALTER A. DANN, a citizen of the United States of America, residing at Cincinnati, in the county of Hamilton and State of Ohio, have invented a new, original, and ornamental Design for Radiator Caps, of which the following is a specification, reference being had to the accompanying drawing, forming part thereof.

Figure 1 is a view in side elevation of a radiator cap showing the new design.

Figure 2 is a top plan view.

I claim:

The ornamental design for a radiator cap, as shown.

In testimony whereof I affix my signature.

WALTER A. DANN.
